(57) **CLAIM**

The ornamental design for battery pack as shown.

DESCRIPTION

FIG. 1 illustrates a front view.

FIG. 2 illustrates a rear view.

FIG. 3 illustrates a bottom view.

FIG. 4 illustrates a top view.

FIG. 5 illustrates a right-side view.

FIG. 6 illustrates a left-side view.

FIG. 7 illustrates a perspective view of the front and top.

FIG. 8 illustrates a perspective view of the bottom and back; and,

FIG. 9 illustrates a perspective view of the top and back.
